UNITED STATES PATENT OFFICE.

WILLIAM FREDRICK BOAST, OF COLBY, KANSAS.

WATER-KEY FOR WIND INSTRUMENTS.

No. 799,707.

Specification of Letters Patent.

Patented Sept. 19, 1905.

Application filed May 2, 1905. Serial No. 258,490.

To all whom it may concern:

Be it known that I, WILLIAM FREDRICK BOAST, a citizen of the United States, residing at Colby, in the county of Thomas and State 5 of Kansas, have invented certain new and useful Improvements in Water-Keys for Wind Instruments, of which the following is a specification.

This invention relates to improvements in 10 water-keys for horns—such as the cornet, trombone, and like musical instruments of the wind type—provided with crooks in which the humidity of the breath when condensed collects and requires to be drawn off; and it 15 consists, essentially, of a member or plate, preferably chambered, having an opening therein and a second member or plate coöperating therewith and preferably of corresponding shape and having an opening and moving 20 in substantially the same plane as the first-mentioned plate.

The invention primarily has for its object 25 to produce a device of this character which will be much simpler and more durable in construction than those commonly in use and which will provide a positive closure for the water-opening while the instrument is being played upon.

Reference is to be had to the accompanying 30 drawings, in which—

Figure 1 is a side elevation of a cornet, showing my improved form of water-valve attached thereto. Fig. 2 is a detail perspective view of the valve. Fig. 3 is a top plan view showing the valve as closed in full lines and as open in dotted lines. Fig. 4 is a longitudinal sectional view on the line $x-x$ of 35 Fig. 3.

Corresponding and like parts are referred 40 to in the following description and indicated in all the views of the drawings by the same reference characters.

In wind instruments it is a well-known fact 45 that the moisture of the breath condenses and accumulates in the tubes, thereby causing a deterioration of the tone, and therefore it is customary to provide a valve for the extraction of this accumulated moisture. The valve as ordinarily constructed comprises, essentially, an opening in the tube and a lever-shaped arm attached by a spring placed under one end and having a piece of cork at the other end to close said opening. The great defect in this form resides in the fact that 55 should the spring become weak or the cork part lose its shape or become lost, as is fre-

quently the case, the pressure from the inside of the instrument when same is being blown is frequently sufficient to slightly open the valve, with the result that there is a decided 60 deterioration in the tone of the instrument.

The numeral 1 designates a chamber which has an opening 2 in the outer side thereof and has a flange 3 extending around its lower edge by means of which it can readily be attached 65 to a musical instrument. Fitting over this chamber 1 is a cap 4, which has a tubular handle 5 and an opening 6 corresponding to the opening 2. This cap 4 is pivotally mounted upon said chamber 1 by means of a screw 70 7 and has a slot 8 in its side which coöperates with a stud 9 on the side of the chamber to prevent said cap from being displaced and also to admit its motion. A spring 10, fastened at one end of the tubular handle 5 and 75 housed therein, is tapered in diameter at its other end and fastened to the stud 9 to normally hold the cap 4 in such a position as to close the valve. This spring 10 may be fastened to the stud 9 in any suitable manner, 80 but is preferably connected thereto by passing its end through an opening therein and then bending it back and twisting it upon itself. It will be noticed that the opening in the handle 5 increases in diameter toward the 85 chamber 1, so that the spring 10 has ample clearance for effective operation. Particular attention is called to the fact that the stud 9 performs a triple function in that it both limits the pivotal motion of the cap 4 and prevents same from being removed and also serves as a means for fastening the spring 10.

As has been before stated, the cap 4 is normally held by the spring so that the valve-openings do not register. In order to open 95 the valve, it is simply necessary to push the handle 5 around until its swinging motion is stopped by the stud 9, the component parts being so arranged that at this point the two valve-openings will register. When the handle is released, the spring will automatically cause the cap to swing around and move the two openings apart, thereby closing the valve.

The valve is intended to be permanently constructed so as to turn either to the right 105 or to the left, as the requirements of the instrument may demand. It will be noticed that there is no cork or similar perishable material employed in the construction of this valve. Another essential feature of the invention resides in the fact that the top of the 110 cap moves in approximately the same plane

as the top of the chamber. In this construction it will be obvious that the pressure on the inside of the instrument can have no tendency to open the valve.

5 From the foregoing description it will be readily understood that I have invented a water-valve for wind instruments which has obvious advantages over those now in use.

Having thus described the invention, what is claimed as new is—

1. A water-valve for horns and like wind instruments comprising a member having an outlet, and a coöperating member for controlling the outlet, having a tubular stem and 15 a spring for holding the last-mentioned member in normal position, said spring being arranged within said tubular stem.

2. A water-valve for horns and like musical instruments comprising a chambered member 20 forming a trap and having a stud projecting from one side thereof and also having an outlet, and a cap pivotally mounted upon and having an opening corresponding to the outlet in the chambered member and also having a slot 25 in the side thereof which coöperates with the stud on the chamber.

3. A water-valve for horns and like musical instruments comprising a chambered member forming a trap and having a stud projecting

from one side thereof and also having an outlet, a cap having a handle, pivotally mounted upon and having an opening corresponding to the outlet in the chambered member and also having a slot in the side thereof which coöperates with the stud on the chamber, and a 35 spring having one end attached to the stud and the other end attached to the handle on the cap to hold the valve normally in a closed position.

4. A water-valve for horns and like musical instruments comprising a chambered member forming a trap and having a stud projecting from one side thereof and also having an outlet, a cap having a tubular handle pivotally mounted upon and having an opening corresponding to the outlet in the chambered member and also having a slot in the side thereof which coöperates with the stud on the chamber, and a spring housed in said tubular handle and attached to the before-mentioned stud 45 to hold the valve normally in a closed position.

In testimony whereof I affix my signature in presence of two witnesses.

WILLIAM FREDRICK BOAST. [L. S.]
